UNITED STATES PATENT OFFICE.

URI HASKIN, OF PITTSBURG, PENNSYLVANIA.

ROLLING-MILL.

SPECIFICATION forming part of Letters Patent No. 269,572, dated December 26, 1882.

Application filed February 18, 1882. (No model.)

To all whom it may concern:

Be it known that I, URI HASKIN, a citizen of the United States, residing at Pittsburg, in the county of Allegheny and State of Pennsylvania, have invented a certain new and useful Improvement in Continuous Trains for Rolling Metals; and I do hereby declare the following to be a full, clear, and exact description thereof, reference being had to the accompanying drawings, forming a part thereof, in which—

Figure 1 is a side elevation of my continuous train of four pairs of rolls, guides, and guide-boxes in position for work. Fig. 2, Plate 2, is a ground plan of Fig. 1. Fig. 3, Plate 2, is a view of the twisted bar as it passes through the train of rolls. Fig. 4, Plate 3, shows a front end view of my continuous train, and Fig. 5, on same sheet, shows the same elevation, with the top section of the housing and top roll thrown back by means of the hinge-joint. Fig. 6, Plate 4, is a side view of housing-rolls and guides when in position, shown in Fig. 5. Fig. 7, Plate 4, shows the oblique arrangement of the top and bottom rolls when in working position. Fig. 8 is a bottom view of the top brass. Fig. 9 is an end view of same. Fig. 10 is a plan view of the bottom brass. Fig. 11 is an end view of same. Fig. 12 is a plan view of the locking-clutch, held out of action by the latch passing over the top of the housing-screw. Fig. 13 is an elevation of same when held out of position. Fig. 14 is a sectional view of housing-rolls, guide, and guide-boxes through the center of the groove. Fig. 15 is an end view of the annular guide-box. Fig. 16 is a plan view of my adjustable box-stretcher. Fig. 17 is an end view of spindle with a stretcher in place. Fig. 18 is an end view of a spindle, box; and Fig. 19 is a view of spindle, boxes, and stretcher in place.

Like letters where they occur are intended to designate like parts of the machine.

My invention relates to continuous trains employed in rolling iron, steel, and, other metals.

In the ordinary practice of rolling metals, when bars or rods are produced the metal escaping from one groove is caught by the workmen with a pair of tongs and turned one-fourth of a revolution and inserted in the next groove. This practice in rod trains running at high ve-

locity is a very laborious and dangerous operation. To obviate this difficulty a continuous train of rolls has been devised composed of a series of horizontal and alternate vertical rolls; but as vertical rolls require bevel-gearing to operate them the wear and tear of such a train is great, and it is costly to keep in repair. A continuous train has also been devised, composed of a series of horizontal rolls with various devices—such as guides, rolls, &c.—for forcibly twisting the bar or rod after it has left one pair of rolls and before it has entered the succeeding rolls; but, having had an extensive experience with a continuous train of the latter class, I have found great difficulty in keeping the twisting machinery in order, and for this reason I have been induced to devise a more perfect, simple, and automatic twisting arrangement, and as the metal often clogs or becomes jammed in the train, when it is necessary to stop the train, slacken all the housing-screws, raise the top rolls, withdraw the twisters, and draw the metal out in the direction in which it entered, which takes time and is a considerable expense, owing to the delay and waste of the hot metal in the furnace.

The second feature of this invention is designed to obviate these difficulties by the use of sectional adjustable housings, to which are attached the guides and guide-boxes, all of which are so constructed and arranged that the top half of the train, consisting of housing-rolls, guides, and guide-boxes, may be readily lifted off of the metal and the bar or rod withdrawn sidewise out of the machine. In order to secure these objects I have invented various devices, so as to enable me to practice my invention, which will be fully explained herein-after.

In the practice of my invention I place the bottom rolls at right angles with the line which the metal travels on, and all of the top rolls except the last one are placed on an oblique line with the bottom rolls, as shown in Fig. 7. By this arrangement the bar or rod is rolled with a sufficient twist so as to bring its horizontal line into a vertical plane at the instant it enters each succeeding groove, and as the last or finishing pair of rolls are both at right angles to the working-line, the rod is delivered in a straight, untwisted condition.

The housings are made sectional and re-

movable by means of a hinge-joint on a line with the working-faces of the rolls, as shown in Figs. 4 and 5 on Plate 3, and are locked when in position for work by means of the 5 hinged stirrup and eccentric *a*. The top guides, *a'* and *a''*, are held in place by the cross-bar *b* and the rod *d* and spring *e*. The top guide-box, *b'*, is held in place by the cross-bar *b*. The bottom guides, *f*, are held in place by the top 10 guides and the guide-rest *g*. The bottom guide-boxes, *h*, are adjustable by means of the plate *i*. In the top of the housing is a water-box, *j*, and on each side of the water-box there are annular openings, in which the spiral springs *e* 15 are placed, so as to keep the guides tight up against the upper rolls without too much friction. The springs rest on the bottom of these annular openings, and the rod to which the guide is attached passes up through the center there- 20 of, as shown in Fig. 17. The housing-screws are provided with locking-clutches to prevent the screws from slackening when the sections are unlocked and the pressure on the tightening-screws is released. On the top of these 25 clutches movable latches are placed, in order to hold the clutch out of place when the screw is to be slackened. This clutch arrangement is shown in Figs. 12 and 13 on Plate 4 in position to slack up the housing-screw.

30 In order to secure a sufficient twist to the bar at all times and at the varying temperature of the metal, the rolls are placed more obliquely than is required under ordinary conditions, and the guides on the delivery side of 35 the rolls are constructed with a normal twist, and, being held rigid, any extra twist is taken out of the metal while passing through them. It will be seen that I do not use these guides as twisting-machines, nor do I claim them as 40 such; but their office is to untwist such bars as may have an excessive twist, and to permit a bar having a normal twist to pass through them unaffected. Just beyond the guides is placed the guide-box having an annular opening of sufficient diameter to permit the twisting-bar to turn and pass forward. Beyond 45 the guide-box are the entering guides of the next pair of rolls, which also have an annular opening of the same diameter as that of the 50 guide-box. This arrangement of the guides and guide-box is shown more fully in Figs. 6 and 17 on Plate 4. The opening in the guide-box *b* is annular. The opening in top and bottom guides *a'* are also annular, while the opening in top and bottom guides *a''* are of a diamond shape of such an arrangement as to allow the metal to pass through with a normal twist. From the guides *a''* the annular opening is continuous to the next pair of rolls. 55

60 In the construction and operation of this train I prefer to use solid journal-boxes, such as shown in Figs. 8, 9, 10, and 11 on Plate 4. These boxes or brasses are held in place by means of the set-screws *k*. The journals are oiled through the oil-opening *l*. The water-box *j* in the top of the housing is used only for cooling the body of the rolls, as I prefer

to use no water on the journals or necks of the rolls. When it becomes necessary to change the bottom rolls it will be necessary to detach the spindle-connection by which they are driven, and in order to facilitate that work I have devised a stretcher which can be more readily put on and taken off than by the old method of tying the stretchers with cord or 70 wire. My improved stretcher is made of two pieces of wood, which are made to fit in the concave grooves of the spindles. These pieces of wood are fastened to plates of spring-steel, so that when the stretcher is in place it is held 75 by the spring, as shown in Figs. 17 and 19, Plate 4.

In the drawings I have shown but four pairs of rolls; but in practice, when a two-inch-square billet is to be rolled into a three-eighths of an 85 inch square rod for railroad-spikes, I use a train of twelve pairs of rolls; and when a two-inch-square billet is to be rolled into a No. 5 rod I use eighteen pairs of rolls in one continuous train. 90

The operation of my continuous train is as follows: The hot iron is placed in the first pair of rolls. The bar is therein reduced to a diamond shape, and by the action of the oblique rolls is caused automatically to pass out of the 95 rolls twisted in such degree as to bring its long axis from a horizontal to a vertical position when it enters the second pair of rolls. The action of these rolls then reduces the metal to a diamond shape, with its long axis horizontal, and delivers it in a twisted condition, the same as the first; and so each pair of rolls except the last pair reduces the bar to a diamond shape, with its long axis horizontal, and delivers it in a twisted condition, so that it 100 may enter the succeeding pair of rolls with the long axis vertical. The last pair of rolls being placed parallel, the rod is delivered from the train in a straight, untwisted condition. 105

As I have found that when iron is rolled in 110 oblique rolls the twisting is greatest when the iron is the hottest and less at a lower temperature, in order to secure a proper twist under all temperatures, I set the obliquity of the rolls to twist from one-third to one-half greater than required, and as the bar escapes out of the 115 rolls it enters the guides, which take out whatever excessive twist there may be in it, and from the untwisting-guides it passes through the annular opening of the guide-box and 120 guide into the succeeding rolls. It will be noticed that the bar is in all of the rolls at the same time. Fig. 3 on Plate 2 shows the shape of a bar taken from three pairs of oblique and one pair of parallel rolls. 125

Should an accident occur while the metal is in the rolls, the train is stopped, the eccentrics are loosened, the stirrups lowered, and the top section of the housing is raised and rested on a stand, *m*, Fig. 5, Plate 3. One minute 130 will be sufficient time to open the entire train in this manner. When thus opened the bar or rod may be withdrawn sidewise, the sections again closed and locked, when the train will

be ready for use. By this arrangement I am enabled to take a bar or cobble out of the train in one-tenth of the time that is required where solid housings are used.

5 In order to relieve the weight of the top section of housing and rolls and make it more easily handled, I use two volute or spiral springs, *n n*, Figs. 2, 4, and 5, Plates 2 and 3. By means of these springs the weight is nearly 10 balanced, so that a man can easily raise a top section almost instantly.

By the use of my continuous train having twelve pairs of rolls, hot bars of iron or steel 15 two inches square may readily be rolled into three-eighths ($\frac{3}{8}$) inch rods at the rate of five hundred (500) feet per minute, or one hundred tons per day of twenty-four hours; and by the use of eighteen pairs of rolls, the last pair of which having a delivery of fifteen hundred feet 20 per minute, one hundred tons of one-quarter ($\frac{1}{4}$) inch rods may be produced per day, leaving ample time for repairs.

In rolling two-inch to a three-eighths from iron I usually draw or reduce the area one-fourth in each pair of rolls except the last. Consequently each succeeding pair of rolls 25 must have an increased speed of twenty-five per cent. The last pairs of rolls only draw about five per cent., and their increased speed 30 must not be over five per cent. When iron rods are drawn smaller than three-eighths of an inch, or when steel is rolled, I advise that the area should not be reduced in any pair of rolls more than twenty per cent., and in that 35 case the increased speed of succeeding rolls should be twenty per cent.

Having described my invention, what I claim, and desire to secure by Letters Patent, is—

1. In a machine for rolling metals, housings 40 formed in two parts joined at or near a plane passing between the working-faces of the rolls, and having the upper roll so arranged in relation to its housings that the former may participate in any motion which may be imparted 45 to the latter, substantially as and for the purpose specified.

2. Roll-housings formed in two parts, joined at or near a plane which will pass between the working-faces of the rolls when they are inserted 50 within said housings, substantially as and for the purpose specified.

3. Housings for a pair of rolls formed in two parts, joined at or near a plane passing between the working-faces of said rolls, and provided 55 with a spring or springs so arranged as to assist in swinging back the upper from the lower section of the housings, substantially as and for the purpose herein specified.

4. In a machine for rolling metals, housings 60 formed in two parts, joined at or near a plane passing between the working-faces of the rolls, and provided with sectional guides and guide-

boxes, the upper sections of which are so arranged in relation to the upper section of the housings that they may participate in any motion which may be imparted to the latter, substantially as and for the purpose herein specified. 65

5. In a machine for rolling metals, housings formed in two sections, pivoted together at or 70 near a plane passing between the working-faces of the rolls, and provided with a locking device to secure the sections together, substantially as and for the purpose herein set forth. 75

6. A continuous train of pairs of horizontal rolls having the rolls of each pair except the last placed obliquely to each other, substantially as and for the purpose specified.

7. A continuous train of pairs of horizontal 80 rolls having the rolls of each pair except the last placed obliquely to each other, and provided with a top and bottom guide between each pair, constructed as specified, whereby the metal may be twisted by the oblique action of the rolls and an excessive twist prevented by the guide, substantially as herein set forth. 85

8. A continuous train of pairs of horizontal 90 rolls having the rolls of each pair except the last placed obliquely to each other, and provided with an annular guide-box between each pair, whereby the metal may be twisted by the rolls while being guided in a straight line for each succeeding pass. 95

9. A continuous train of pairs of horizontal 100 rolls having the upper rolls mounted severally in removable sectional housings provided with tightening-screws having locking-clutches, whereby the screws may be retained in proper position after the housing-sections are unlocked and the pressure on the tightening-screws relieved, substantially as specified.

10. In a machine for rolling metals, housings 105 formed in two sections, joined at or near a plane passing between the working-faces of the rolls, having sectional guides and guide-boxes, arranged as specified, and provided with a spring or springs to aid in removing the upper sections of the housings, substantially as and for the purpose specified. 110

11. A continuous train of pairs of horizontal 115 rolls mounted in sectional housings, constructed and arranged to operate as specified, whereby the top section of the housings of each or all the pairs of rolls may be readily swung away or removed to permit repairs, replacement of guides, guide-boxes, and rolls, or the removal of cobbles, substantially as and for the purpose specified.
